John Smith
Design for Lacis Cloth
Patented Sept 3, 1852

Design No. 444 —

Fig 1:

Dec. 444

Jas. Shields, of Fishkill N.Y.
Letters Patent No 444. Dated Feb 3. 1852.

The Schedule referred to in these Letters Patent, and making part of the same:

To all whom it may concern:

Be it known that I, James Shields of the Town of Fishkill of the County of Dutchess and State of New York, have invented or produced a new and original design for the top of a Ladies Hair Comb, and I do hereby declare that the following is a full and exact description of the same, reference being had to the annexed drawing, making a part of the description. Fig: 1st is a view of the front side of the comb.

Fig: 2nd is an end view shewing the coil as it is formed; the design consists of a coil formed over the tops of the teeth which is turned from the front to the back side of the comb. What I claim to be new and original and desire to be secured by Letters Patent, is the design and configuration of a Ladies Hair Comb, as described above and represented in Figures 1st and second.

Witnessed

G. W. Van Derburgh
P. J. Groot

Jas. Shields.
